(57) CLAIM

The ornamental design for a pool float featuring a human figure projecting from a tube, as shown and described.

DESCRIPTION

FIG. 1 is a top, front perspective view of a design for a pool float featuring a human figure projecting from a tube;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top, rear perspective view thereof;

FIG. 9 is a bottom, rear perspective view thereof;

FIG. 10 is a top, front perspective view thereof with unclaimed artwork thereon approximating a political figure and political designs;

FIG. 11 is a top, front perspective view thereof with unclaimed artwork thereon approximating a political figure and political designs; and,

FIG. 12 is a bottom, rear perspective view thereof with unclaimed artwork thereon approximating a political figure and political designs.

The broken lines showing of portions of the design depicts environment and forms no part of the claim.

1 Claim, 12 Drawing Sheets
